UNITED STATES PATENT OFFICE.

CHARLES W. FRAIM, OF HARRISBURG, PENNSYLVANIA.

PUZZLE.

SPECIFICATION forming part of Letters Patent No. 716,697, dated December 23, 1902.

Application filed October 10, 1902. Serial No. 126,793. (No model.)

To all whom it may concern:

Be it known that I, CHARLES W. FRAIM, a citizen of the United States, residing at Harrisburg, in the county of Dauphin and State 5 of Pennsylvania, have invented new and useful Improvements in Puzzles, of which the following is a specification.

This invention relates to certain new and useful improvements in puzzles; and the purpose of the same is to provide a device of this 10 class of a simple and effective construction which will be amusing and require skill and ingenuity to arrive at its solution.

The invention consists in the construction 15 and arrangement of the several parts, which will be more fully hereinafter described and claimed.

In the drawings, Figure 1 is a perspective view of a puzzle embodying the features of the 20 invention. Fig. 2 is a horizontal section of the same. Fig. 3 is a transverse vertical section taken in a plane to one side of the center on the line 3 3, Fig. 2.

Similar numerals of reference are employed 25 to indicate corresponding parts in the several views.

The numerals 1 and 2 designate centrally-intersecting vertical partitions, which are immovably secured to each other by suitable 30 means, and the one end of the partition 1 is formed with an angular flange 3. Each of the partitions has a pair of openings 4 therein, which are located above the lower edge of the same. Both partitions are of equal vertical extent, and where they intersect are slotted 35 to cause them to more firmly interlock. The connected partitions are surrounded by a circular shell or casing 5, having upper and lower inturned angular flanges 6, between which and the upper and lower edges of the 40 said partitions are top and bottom glass plates 7, which give full view to the interior of the puzzle. The ends of the partitions 1 and 2, and particularly the flanged end 3 of the partition 1, are secured to the inner surface of the shell or casing 5, and to render the puzzle 45 structure more strong and durable it is preferably entirely formed of metal, except the plates 7.

50 In the assemblage of the parts the one edge of the shell or casing 5 is first flanged and the one plate and the interlocked partitions are disposed therein and secured by the use of

solder or other similar material applicable for the purpose. Before the puzzle is completely 55 sealed a number of small balls or shot are introduced in one of the cells constructed by the intersecting partitions in relation to the surrounding shell or casing, and the remaining glass plate is then placed on the still open 60 end of the puzzle and the opposite edge of the shell or casing is flanged over said plate, to thereby fully seal the puzzle to prevent access to the interior thereof. In this condition 65 the puzzle is ready for solution.

The solution of the puzzle consists in manipulating the same in such manner as to cause the balls or shot to be thrown or passed through the openings 4 until each cell shall contain one ball, as indicated by dotted lines 70 in Fig. 2, and in view of the elevation of the openings 4 above the bottom edges of the partitions or at an equal distance from both the upper and lower edges of said partitions considerable ingenuity will be required on the 75 part of the operator to cause the balls or shot to pass through the said openings. During the solution of the puzzle it may be turned in any position, and a source of amusement is provided at a minimum cost, as it is preferred 80 to form the partitions and shell or casing of tin or other cheap sheet metal.

Having thus fully described the invention, what is claimed as new is—

A puzzle, comprising a surrounding shell 85 or casing of circular form, intersecting partitions secured to the casing and forming a series of four cells, the said partitions extending fully to opposite ends of the casing and the portions thereof between each two 90 cells having openings therethrough, all of equal diameter and located at equal distances from upper and lower edges of the partitions, transparent plates interposed between the opposite edges of the shell or casing and the 95 ends of the partitions, and a series of balls within the casing corresponding in number to the number of cells formed by the partitions.

In testimony whereof I affix my signature 100 in presence of two witnesses.

CHARLES W. FRAIM.
